UNITED STATES PATENT OFFICE.

JOSEPH ALRICK LEGRANDEUR, OF TORONTO, ONTARIO, CANADA.

JEWELER'S PIN-POINTER.

1,347,547.

Specification of Letters Patent.

Patented July 27, 1920.

Application filed May 6, 1919. Serial No. 295,140.

To all whom it may concern:

Be it known that I, JOSEPH ALRICK LEGRANDEUR, of the city of Toronto, in the county of York, in the Province of Ontario, Canada, have invented certain new and useful Improvements in Jewelers' Pin-Pointers, of which the following is the specification.

My invention relates to improvements in jewelers' pin pointers and the object of the invention is to devise a simple and cheap device whereby pins may be pointed in a minimum amount of time and with a minimum amount of labor and it consists essentially of the arrangement and construction of parts as hereinafter more particularly explained.

Figure 1, is a perspective view of my device.

Fig. 2, is a sectional view through Fig. 1, taken from side to side.

Fig. 3, is a sectional view through Fig. 1 taken from back to front.

Fig. 4, is a detail of the pin holder.

Fig. 5, is a detail of the cutting knife.

In the drawings like characters of reference indicate corresponding parts in the various figures.

1 indicates a shank which is adapted to be secured in a lathe chuck. 1^x indicates the tool body which is formed integral with the shank. 1° indicates an orifice, which extends horizontally through the body, the lower front portion of which is provided with an upwardly inclined face 1'. The upper portion is provided with an extension 1², the base 1³ of which is located exactly on the center line of the tool. The upper portion of the base of the extension is stepped forwardly at 1⁴ terminating in an upwardly inclined wall 1⁵. 1⁶ indicates an orifice which extends upwardly into the body from the bottom into the orifice 1° and is located centrally of the tool.

3 indicates a pin holder, which comprises a sleeve extending up into the orifice 1⁶ and held therein by a screw 4. The lower portion of the sleeve is flared outwardly at 3^x to form a mouth to receive the pin. The upper end of the holder is notched at 3°, the base of the notch being exactly upon the center line of the tool and on the center line of the orifice of the sleeve 3. The orifice of the sleeve 3 is provided at its upper end with a tapered portion 3' terminating at its apex at the upper end of the notch 3°.

5 indicates the cutter, which comprises a horizontal portion 5^x and a vertical portion 5' provided with a cutting edge 5² which is inclined to correspond with the taper of 60 the pin point designed to be cut.

When the cutter is in position within the tool the upper end of the cutting edge as will be clearly seen on referring to Fig. 2 meets the apex of the tapered portion of the 65 orifice of the pin holder 3.

6 indicates a block which is provided with inclined upper and lower ends 6^x and 6° fitting the portions 1⁵ and 1' of the body of the tool. The inner face of the block 6 is 70 provided with an inclined extending portion 6° which is recessed at 6² to allow space for the holder 3 which bears against the horizontal portion 5^x of the cutter 5. The upper portion of the block 6 is provided with clearance between such block and the base of the recessed portion 1⁴. 7 indicates a set screw which passes through the block 6 into the body of the tool. By screwing such screw home the upper portion of the block 6 is 75 drawn inwardly, the lower portion of the block being drawn outwardly, being fulcrumed upon the inward extension 6' which bears upon the cutter portion 5^x thereby securing the cutter in place. 80

8 indicates a pin. The unpointed pin is passed upwardly through the orifice of the holder 3, the cutting tool being revolved. As the pin 8 is forced upwardly it engages the cutting edge 5² of the knife 5 and as the tool revolves and the pin is forced upward a tapered point is cut which gradually enters and fits the tapered portion 3' of the orifice of the holder 3 and thereby is held securely and firmly in position so that it cannot get away from the cutter as the cutter revolves in contact therewith gradually cutting the point. The cuttings as they are formed drop away through the back portion of the orifice 1°.

From this description it will be seen that I have devised a very simple device whereby jewelers' pins may be quickly and easily pointed and which dispenses with the expensive machinery which has heretofore been required to perform this operation.

What I claim as my invention is:

1. A jeweler's pin pointer comprising a revolving member having a pin receiving orifice extending axially thereinto, a cutter having its cutting edge inclined to correspond with the taper of the pin point and

- against which the pin is carried by longitudinal pressure and means extending longitudinally of the pin and forming a bed for the pin extending from the extreme point of 5 the pin when the cutting operation is completed and whereby the pin is held rigidly in position against the pressure produced by the operation of the cutter preventing the 10 springing of any portion of the pin out of the cutting position.
2. A jeweler's pin pointer comprising a shank adapted to be revolved, a tool body carried by the shank having a cross orifice and a vertical orifice extending from the 15 end of the tool into the cross orifice, a pin holder secured in the vertical orifice and having a pin receiving bore and having its upper end notched to the central line of the holder, a tapered extension to the bore 20 terminating at its apex at the upper end of the notched portion, a cutting tool having outwardly inclined cutting edge extending from the apex of the pin holder orifice, and

means for securing the cutting tool in position.

3. A jeweler's pin pointer comprising a body adapted to revolve on its longitudinal axis and having a cross orifice and a longitudinal orifice, a pin holder fitting the longitudinal orifice having a longitudinal bore 30 terminating in a tapered upper end, a notch formed in the upper end of the holder having its base located on the central line of the holder and in which the tapered portion of the bore is located; a cutter comprising a 35 rectangular member fitting within the body and having an outwardly inclined cutting edge extending from the apex of the tapered portion of the bore of the pin holder, and a clamping device bearing against the horizontal portion of the cutter for holding the 40 cutter in place.

JOSEPH ALRICK LEGRANDEUR.
